ILLUMINATED GUITAR

Louis Leon Canonicco, Bronx, N.Y., assignor of thirty-three and one-third percent to Michael Nicita, Kendall Park, N.J.

Filed July 15, 1965, Ser. No. 472,126
14 Claims. (Cl. 84—267)

This invention concerns an illuminated guitar.

The purpose of the invention is to provide a guitar having an illuminated neck and other parts so that when the guitar is played in a dim light it will present a spectacular display. According to the invention, the guitar has a neck made of transparent plastic material such as methyl methacrylate. The bridge of the guitar and a portion of the body under the strings are also formed of the same material. Lamps in the hollow body of the guitar illuminate the plastic parts. The lamps may emit colored light or the illuminated plastic parts can be made of colored plastic. The guitar can be arranged so that the lights flicker while the guitar is being played to provide novel visual effects.

It is therefore one object of the invention to provide a guitar with transparent plastic parts which glow when illuminated to provide a spectacular optical display.

Another object is to provide a guitar in which lamps illuminating transparent plastic parts of the guitar are disposed inside the hollow body of the guitar and controlled by switches outside the guitar.

Still another object is to provide a guitar with illuminated plastic parts illuminated by lamps which flicker when the guitar is being played.

For further comprehension of the invention, and of the objects and advantages thereof, reference will be had to the following description and accompanying drawings and to the appended claims in which the various novel features of the invention are more particularly set forth.

In the accompanying drawings forming a material part of this disclosure:

FIGURE 1 is a perspective view of an electric guitar embodying the invention, shown with an associated amplifier.

FIG. 2 is a fragmentary sectional view of an electric guitar on an enlarged scale taken on line 2—2 of FIG. 1.

FIG. 3 is a fragmentary enlarged cross sectional view taken on line 3—3 of FIG. 1.

FIG. 4 is a fragmentary bottom plan view taken on line 4—4 of FIG. 2.

FIG. 5 is a reduced perspective view of a bottom cover plate of the guitar.

FIG. 6 is a diagram of an electric circuit employed in the guitar of FIGS. 1—5.

FIG. 7 is a diagram of another electric circuit which may be employed in the guitar of FIGS. 1—5.

FIG. 8 is a longitudinal sectional view similar to FIG. 2 showing another guitar construction.

FIG. 9 is an exploded perspective view on a reduced scale of parts of the guitar of FIG. 8.

FIG. 10 is an exploded perspective view of a fret and associated components employed in the guitar of FIG. 8.

FIG. 11 is a diagram of an electric circuit employed in the guitar of FIG. 8.

The guitar 10 shown in FIGS. 1—5 has a flat opaque hollow body 11 with a top wall 12, peripheral wall 13 and open bottom closed by a reflector plate 14. An elongated neck 15 extends outwardly of one end of body 11. The body 11 including plate 14 is made of opaque material. The neck 15 is made of transparent plastic material, particularly an acrylic such as methyl methacrylate which has the property of glowing peripherally when illuminated, internally. As clearly shown in FIG. 2, the attached

2

end 15' of the neck is exposed to the interior of the body 11. Secured to the underside of the upper wall 12 of body 11 are brackets 20 which support three lamps 21. The end 15' of neck 15 is exposed to the lamps so that when the lamps are lighted, light therefrom will enter the neck along optical path P1 and will travel internally therethrough. The entire periphery of the neck including top, bottom and sides including scroll end 15" will light up to produce a striking optical spectacle when viewed in a dim ambient light. Neck 15 is held by a screw 23 inserted through end 15' of the neck and inserted in tenon 27 at the rear end of the body engaged in a groove 29 in the end of the neck.

In the wall 12 of body 11 is an opening 24 in which is fitted a transparent plastic lens or window 25. The window is also made of an acrylic plastic. The window opens at its bottom to the interior of the hollow body. The bottom of the window is exposed to the light of lamps 21 both directly and by reflected light; see FIG. 2, 3. Light is reflected in path P2 from the highly polished upper surface S of cover plate 14 which closes the open bottom of body 11. The cover plate is removable secured to the bottom edge of wall 13 by screws 26.

In upper wall 12 is a long aperture 30 in which is fitted the flat bottom of wedge shaped bridge 32. The bridge is also made of acrylic plastic. The bottom end of the bridge is exposed to the interior of the body 12. At opposite ends of the bridge inside the body 11 are two lamps 34 supported by brackets 36 attached to the underside of wall 12. These lamps illuminate the bridge and cause it to glow peripherally at all exposed sides on the neck of the guitar. The strings 38 of the guitar extend from pegs 39 at neck end 15" over bridge 32 to tail piece 40 which is held by pin 41 in wall 13. Frets 43 are set in neck 15.

The three lamps 21 are connected via wires in circuit with three manually operable control switches 42 located at one corner of the upper wall 12. Lamps 34 are connected via wires in circuit with a switch 44 located at one lateral edge of wall 12. A jack 45 is provided near switch 44 into which a plug 46 can be inserted for applying electric power to the lamps. The jack 45 is connected in circuit with the lamps 21 and 34.

Between the bridge and window 25 is a first microphone 48. A second microphone 50 is located between window 25 and the adjacent end of neck 15.

A jack 52 on wall 12 and a switch 53 are connected in circuit with the microphones. Jack 52 may receive a plug 54 connected via a cable 56 and plug 57 to jack 58 in an amplifier housing 60. Plug 46 is connected to cable 62 which terminates in a plug 63. The plug can be inserted in a jack 64 connected to a power transformer in the amplifier housing. The arrangement of the electric circuit C1 employed in the guitar 10 is shown in FIG. 6 to which reference is now made.

In circuit C1, there is provided a stepdown power transformer 70 having a primary winding 71 to which is connected power supply cable 72 terminating in a plug 75; see also FIG. 1. Plug 75 can be inserted into a suitable 110-volts alternating current power supply. Transformer 70 has a low voltage secondary winding 76 which is connected to jack 64. Switch 44 is connected in series circuit with both parallel interconnected lamps and jack 45. Plug 46, inserted in this jack, is connected in circuit with the transformer secondary winding cable 62, plug 63 and jack 64. Switches 42 are connected in series with the lamps 21 respectively for turning each lamp individually on and off. The switches 42 and lamps 21 are connected in parallel with lamps 34 to the terminals of secondary winding 76 via the cable 62 and associated plugs and jacks.

The secondary winding 76 is also connected to amplifier 60'. A loudspeaker 77 mounted in housing 60 is connected to the output of the amplifier. To the input of the amplifier is connected parallel connected microphones 48, 50 via control switch 53, plugs 54, 57 and cable 5.

From an inspection of circuit C1 it will be apparent that the illumination of bridge 32 by lamps 34 can be turned off and on by operating switch 44. The illumination of the window 25 and neck by lamps 21 can be turned off and on by operating switches 42. The number of lamps 21 illuminated at any one time can be varied by turning on or off one or more switches 42. As a result varying spectacular optical display is provided when the guitar is viewed in ambient light of reduced intensity.

FIG. 7 shows another circuit C2 which is similar to circuit C1 and corresponding parts are identically numbered. In this circuit a relay 80 having a coil 81 and normally open contacts 82, 83 is provided. The coil 81 is connected across the output of amplifier 60'. The contacts 82, 83 are connected between one terminal of jack 64 and one terminal of secondary winding 76. A normally open manually operable switch 85 is connected across contacts 82, 83 to shunt them when required.

Circuit C2 is arranged so that the lamps 21 and 34 will normally be extinguished even though switches 42 and 44 are closed. However, when the guitar is being played microphones 48, 50 pick up the sounds and translate them into audio frequency electrical pulses which are applied to the amplifier 60'. These pulses are applied to loudspeaker 77 and to the relay coil 81 via a rectifier 84. Each time an electrical pulse of predetermined amplitude applied to the relay coil it closes contacts 82, 83 and the lamps 21 and 34 light up depending on which of switches 42 and 44 are closed. This provides a most interesting and spectacular flickering light display. If switch 85 is closed the relay contacts are shunted and deactivated in the circuit. Then the switches 42 and 44 can be operated manually to control the light of the lamps in the same way as explained in connection with circuit C1.

FIGS. 8, 9 and 10 show another guitar 10a in which parts corresponding to those of guitar 10 are identically numbered. The metal base or back cover plate 14a is provided with a metal plate extension 90 secured by a screw 92 to the rear end 93 of plate 14a. Plate 90 has holes 91. It is permanently affixed to the underside of the neck by peening the bottom ends 95 of metal pins 96 secured to transverse frets 43a. Pin ends 95 are seated in countersunk holes 91. The strings 38a are made of metal music wire and are secured to metal tail piece 40. A lug 98 and wire 99 are engaged with pin 41 and tail piece 40. Another lug 100 and wire 102 are engaged with screw 103 at cover plate 14a. Wires 99 and 102 are connected in circuit C3 shown in FIG. 11. Parts of circuit C3 corresponding to those of circuits C1 and C2 are identically numbered and have the same functions.

The strings 38a are normally spaced from the frets 43a and are pressed down thereon when the guitar is played as illustrated in FIG. 9. It will be noted in FIG. 11 that the strings 38a are all connected electrically together at tail piece 40 and wire 99 to contacts 42' of switches 42. A manually operable switch 110 is connected between wire 99 and wire 102. Wire 102 is connected electrically to all frets 43a. Wire 102 terminates at one terminal of the transformer secondary 76 of power transformer 70. Switch 44 is connected in series with lamps 34. Switches 42 are connected in series with the lamps 21 respectively. Microphones 48, 50 are connected to the input of amplifier 60' and loudspeaker 77 is connected to the output of the amplifier as in circuits C1 and C2.

In operation of circuit C3, when switches 42 and 44 are closed the lamps 21 and 34 will remain unlighted because the power supply circuit of the lamps is open across frets and strings. When any string is pressed down to intact any fret, the power supply circuit of the lamps

will be closed and the lamps will light unless their switches 42 or 44 are open. Thus as the guitar is played the light of the lamps will flicker and a flickering spectacular, interesting, optical display will be provided at bridge 32, window 25 and along the entire length of neck 15. If switch 110 is closed, the strings and frets will be shunted and deactivated on the circuit which will then operate like circuit C1. The lamps will remain lighted when the switches 42 and 44 are closed.

Although a particular arrangement of luminous plastic parts has been shown, it will be apparent that other openings can be provided in the body 11 for receiving other windows of different sizes and shapes. Instead of an electric guitar, the invention is applicable to other types of guitars and to other musical instruments.

While I have illustrated and described the preferred embodiments of my invention, it is to be understood that I do not limit myself to the precise constructions herein disclosed and that various changes and modifications may be made within the scope of the invention as defined in the appended claims.

What is claimed is:

1. A guitar having a closed hollow body defined by a plurality of opaque walls, at least one lamp mounted inside the body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck.

2. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic bridge secured in said opening and having a portion exposed to the interior of said body, another lamp mounted inside said body at said bridge for illuminating the same to cause the bridge to glow, when said other lamp is lighted, and other wires connected to said other lamp for supplying the same with electric current.

3. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic bridge secured in said opening and having a portion exposed to the interior of said body, another lamp mounted inside said body at said bridge for illuminating the same to cause the bridge to glow, when said other lamp is lighted, and other wires connected to said other lamp for supplying the same with electric current, said one wall having another opening therein, and a transparent plastic window disposed in said other opening, said window having a portion exposed to the interior of the said body and to said one lamp so that said window glows when said one lamp is lighted.

4. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck

gloves over its entire outside surface when light from said lamp passes through said end of the neck, one of said walls having an opening therein, a transparent plastic bridge secured in said opening and having a portion exposed to the interior of said body, another lamp mounted inside said body at said bridge for illuminating the same to cause the bridge to glow, when said other lamp is lighted, and other wires connected to said other lamp for supplying the same with electric current, said one wall having another opening therein, and a transparent plastic window disposed in said other opening, said window having a portion exposed to the interior of the said body and to said one lamp so that said window glows when said one lamp is lighted, and switches mounted on said body and connected in circuit with the lamps for selectively turning the lamps on and off when the switches are operated.

5. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic window disposed on said opening, said window having a portion exposed to the interior of said body and to said lamp so that said window glows when said lamp is lighted.

6. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic window disposed on said opening, said window having a portion exposed to the interior of said body and to said lamp so that said window glows when said lamp is lighted, and a switch mounted on said body and connected in circuit with said lamp for turning the lamp on and off when the switch is operated.

7. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, strings supported at opposite ends thereof on said body and said neck respectively, at least one microphone mounted on said body adjacent to said strings for picking up sounds emitted therefrom when the strings are plucked, an amplifier having input and output terminals, said microphone being connected to said input, a relay having a coil connected to the output terminals of the amplifier, said relay having contacts operated by said coil and connected in circuit with said lamps, whereby the light of said lamps flickers when the strings are plucked.

8. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic window

disposed on said opening, said window having a portion exposed to the interior of said body and to said lamp so that said window glows when said lamp is lighted, said body having a removable back wall with a highly reflective surface to reflect light from said lamp to the window and neck to intensify the glow thereof.

9. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic bridge secured in said opening and having a portion exposed to the interior of said body, another lamp mounted inside said body at said bridge for illuminating the same to cause the bridge to glow, when said other lamp is lighted, and other wires connected to said other lamp for supplying the same with electric current, said one wall having another opening therein, and a transparent plastic window disposed in said other opening, said window having a portion exposed to the interior of the said body and to said one lamp so that said window glows when said one lamp is lighted, said body having a removable back wall with a highly reflective surface to reflect light from the lamps to said bridge, window and neck to intensify the glow thereof when the lamps are lighted.

10. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic bridge secured in said opening and having a portion exposed to the interior of said body, another lamp mounted inside said body at said bridge for illuminating the same to cause the bridge to glow, when said other lamp is lighted, and other wires connected to said other lamp for supplying the same with electric current, said one wall having another opening therein, and a transparent plastic window disposed in said other opening, said window having a portion exposed to the interior of the said body and to said one lamp so that said window glows when said one lamp is lighted, said body having a removable back wall with a highly reflective surface to reflect light from the lamps to said bridge, window and neck to intensify the glow thereof when the lamps are lighted.

11. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, metal strings supported at opposite ends thereof on said body and said neck, a metal tail piece engaged with one end of said strings on said body, said body having a removable metal back wall, a metal plate defining an extension of said back wall extending along one side of said neck, metal frets on the other side of said neck extending transversely thereof underneath the strings, metal pins connecting said frets respectively with said metal plate, a power supply, said wires being connected in circuit with said power supply, and other wires connecting said tail piece and said back wall in circuit with said power supply, whereby said lamp is normally extinguished and is lighted when any one of said strings is pressed down on the neck to contact any one of the frets.

12. A guitar having a closed hollow body defined by a plurality of opaque walls, at least one lamp mounted

side said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, metal strings supported at opposite ends thereof on said body and said neck, a metal tail piece engaged with one end of said strings on said body, said body having a removable metal back wall, a metal plate defining an extension of said back wall, extending along one side of said neck, metal frets on the other side of said neck extending transversely thereof underneath the strings, metal pins connecting said frets respectively with said metal plate, a power supply, said wires being connected in circuit with said power supply, and other wires connecting said tail piece and said back wall in circuit with said power supply, whereby said lamp is normally extinguished and is lighted when any one of said strings is pressed down on the neck to contact any one of the frets, manually operable switch connected in parallel with said frets and strings for deactivating said frets and strings in said power supply circuit, and other switches connected in circuit with said lamps for selectively turning the lamps on and off when the first named switch is closed, and for selectively keeping the lamps turned off when said first switch is open to permit the lamps to flicker while the strings are played.

13. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic window disposed on said opening, said window having a portion exposed to the interior of said body and to said lamp so that said window glows when said lamp is lighted, and a switch mounted on said body and connected in circuit with said lamp for turning the lamp on and off when the switch is operated, strings supported at opposite ends thereof on said body and said neck respectively, at least one microphone mounted on said body

adjacent to said strings for picking up sounds emitted therefrom when the strings are plucked, an amplifier having input and output terminals, said microphone being connected to said input, a relay having a coil connected to the output terminals of the amplifier, said relay having contacts operated by said coil and connected in circuit with said lamps, whereby the light of said lamps flickers when the strings are plucked.

14. A guitar having a closed hollow body defined by a plurality of opaque walls, at least one lamp mounted inside said body, wires connected to the lamp for supplying electric current thereto, a neck made of transparent plastic material connected to an end of said body, said neck having an end thereof exposed to the interior of the body for receiving light from said lamp whereby said neck glows over its entire outside surface when light from said lamp passes through said end of the neck, one of said walls having an opening therein, a transparent plastic window disposed on said opening, said window having a portion exposed to the interior of said body and to said lamp so that said window glows when said lamp is lighted, and a switch mounted on said body and connected in circuit with said lamp for turning the lamp on and off when the switch is operated, metal strings supported at opposite ends thereof on said body and said neck, a metal tail piece engaged with one end of said strings on said body, said body having a removable metal back wall, a metal plate defining an extension of said back wall extending along one side of said neck, metal frets on the other side of said neck extending transversely thereof underneath the strings, metal pins connecting said frets respectively with said metal plate, a power supply, said wires being connected in circuit with said power supply, and other wires connecting said tail piece and said back wall in circuit with said power supply, whereby said lamp is normally extinguished and is lighted when any one of said strings is pressed down on the neck to contact any one of the frets.
